DESIGN FOR A COMBINED EVENING AND STREET DRESS

Doris Mandelker, New York, N. Y.

Application July 29, 1941, Serial No. 102,525

Term of patent 3½ years

To all whom it may concern:

Be it known that I, Doris Mandelker, a citizen of the United States of America, residing in New York city, county of New York, and State of New York, have invented a new, original, and ornamental Design for a Combined Evening and Street Dress, of which the following is a specification, reference being had to the accompanying drawing, forming part thereof.

Fig. 1 is a front view of a combined evening and street dress showing my new design.

Fig. 2 is a rear view thereof on a smaller scale.

Fig. 3 is a front view on a smaller scale of the dress shown in Fig. 1 with the lower skirt portion thereof omitted.

Fig. 4 is a rear view of Fig. 3.

I claim:

The ornamental design for a combined evening and street dress, substantially as shown.

DORIS MANDELKER.
